UNITED STATES PATENT OFFICE.

LEE FRASIER, OF FREDERICK, OKLAHOMA.

STOVEPIPE-CLEANER.

1,310,525.

Specification of Letters Patent.

Patented July 22, 1919.

Application filed January 11, 1918. Serial No. 211,379.

To all whom it may concern:

Be it known that I, LEE FRASIER, a citizen of the United States, residing at Frederick, in the county of Tillman and State 5 of Oklahoma, have invented certain new and useful Improvements in Stovepipe-Cleaners, of which the following is a specification.

This invention relates to new and useful 10 improvements in stove pipe cleaners, and an important object of my invention is to provide a device whereby the scraping element thereof, is held in close engagement with the interior wall of the pipe.

Another object of my invention is to provide a device including a scraping element 15 which operates within a stove pipe for removing soot therefrom, and may be operated by a member which extends upon the 20 outside of the pipe.

Another object of my invention is to provide a device of the above mentioned character including means whereby the scraping element may be removed for repairing or 25 replacing the same.

Other objects and advantages of my invention will become apparent during the course of the following description.

In the accompanying drawings forming 30 a part of the description and wherein like numerals are employed for designating like characters throughout the same—

Figure 1 is a fragmentary view of the usual stove pipe with my invention applied 35 thereto; and,

Fig. 2 is a bottom plan view of the same.

Fig. 3 is an elevation of the coupling.

Fig. 4 is an elevation of a modified form 40 of the cleaner handle.

In the drawings, wherein for the purpose of illustration is shown the preferred embodiment of my invention the numeral 1 designates the usual stove pipe which is provided with the usual elbow joint 2, in the 45 outer curved surface of which is provided an opening for a purpose which will presently appear.

My improved cleaner consists of an elongated rod 3 adapted to pass and operate 50 through the above named opening, the upper end of which is looped as at 4 to provide a finger grip.

This rod 3 extends down into the section 55 of the pipe 1 and is arranged centrally therein. The lowermost end of this rod 3

is bent at substantially right angles, outwardly, to form the upper horizontal portion 5, and is then curved outwardly and downwardly as at 6, then inwardly to form the horizontal portion 7. By bending the 60 rod in the manner set forth, it will be seen that the portion 6 is adapted to snugly engage the interior wall of the pipe at one point only on the inner periphery of the pipe. This goose neck also possesses a resiliency 65 for a purpose which will presently appear. The free end of the horizontal portion 7 extends past the center of the pipe 1 and is then curved upwardly as at 8 a substantial distance above the upper horizontal portion 5. The free end of the portion 8 is adapted to be arranged a substantial distance from the wall of the interior of the pipe, but owing to its resilient character, normally tends to engage with the interior 70 wall. The free end of the portion 8 is threaded, as more clearly indicated by the numeral 9 of Fig. 1, and is adapted to receive the raking or cleaning element 10.

This cleaning element is provided with a 80 substantially semi-circumferential outer edge 11 which is substantially cut from a circular piece of metal having substantially the same radius as that of the interior of the stove pipe. The inner marginal edge 12 is curved 85 outwardly toward the outer circumference of the raking element at both ends to form the pointed terminals 13 of the scraping element. Nuts 14 are adapted to be received on the threaded ends 9 of the curved portion 8 90 and are adapted to clamp against the opposite faces of the scraping element. By the resiliency of the goose neck it will be readily recognized that the outer marginal edge of the scraping element is brought into close 95 engagement with the interior wall of the stove pipe.

The rod 3 and the goose neck may be formed from a single strand of resilient wire or they may be formed in two separate sections, each section having a looped end adapted to be received in the channel iron coupling 15 and secured therein by means of bolts 16.

In use, when it is desired to remove the 105 soot from the inner wall of the stove pipe, the rod 3 is turned so that the scraping element is in a position so that the outer marginal edge engages the upper interior surface of the horizontal stove pipe. The rod 110

3 is then pushed into the pipe until the loop 4 engages the elbow 2. During this operation it will be seen that the goose neck forces the scraping element into close engagement with the interior surface of the pipe, and as it moves along the same the soot will be scraped from the upper interior surface and will drop down upon the lower wall. The loop 4 is then twisted so that the 10 cleaning element slides down the curved wall of the pipe until the outer periphery of the scraping element engages the assumed lower side of the pipe. The loop 4 is then grasped and moved outwardly so that the rod 3 moves the cleaning element toward the stove, and rakes with it the soot which has been 15 cleaned from the upper interior surface of the pipe together with that which has collected upon the lower interior surface. The 20 pointed ends 13 of the scraping element will facilitate said element being readily turned in the pipe and to cut through the soot which has collected upon the lower interior surface.

25 It is to be understood that the form of my invention herewith shown and described is to be taken as a preferred embodiment of the same and that various changes in the shape, size and arrangement of parts may 30 be resorted to without departing from the spirit of the invention or the scope of the sub-joined claims.

I claim:

1. A stove pipe cleaner including a handle

provided with a spring member engaging the inner wall of a pipe at one point on its periphery, and a scraping element carried by said spring member and retained in close engagement with the interior wall of the pipe by said spring member engaging the 35 opposite side of the pipe.

2. A stove pipe cleaner including a wire handle, said handle having its lower end bent outwardly to form a spring member engaging the inner wall of a pipe, and a 45 semi-circumferential plate secured to the free end of the spring member and retained in close engagement with the interior wall of a pipe by said member engaging the opposite side of the pipe.

3. A stove pipe cleaner including a resilient handle, the end of said handle being bent to form a spring member to yieldingly engage the inner periphery of the pipe at one point only and bent toward the opposite side of the pipe to be arranged in close proximity with said side, and a scraping element carried by said end and yieldingly retained in close engagement with said pipe by said spring member engaging the opposite side of the pipe.

In testimony whereof I affix my signature in presence of two witnesses.

LEE FRASIER.
